METHOD AND APPARATUS FOR MAKING
PAPER BAGS

Howard A. Wolf, Philadelphia, Pa., assignor to
Louis Wolf, Howard A. Wolf, and Elias Wolf,
copartners, doing business as Wolf Brothers,
Philadelphia, Pa.

Application May 18, 1932, Serial No. 611,960

11 Claims. (Cl. 93—19)

This invention relates to an improvement in method and apparatus for making paper bags, and more particularly to the making of paper bags of the flat or envelope type and having a long lip or closure flap.

Heretofore the production of paper bags or envelopes having a long lip or closure flap has entailed complicated procedure and the use of machinery presenting complication in its structure and operation and at the same time expensive to produce and maintain.

Thus, for example, paper bags or envelopes of the type contemplated have been produced by the formation of a paper tube, slitting opposite sides of the tube longitudinally at intervals and finally, and as a separate operation, severing the tube into lengths by transverse cuts connecting the ends of the longitudinal slits. Such procedure is, for example, shown by the patent to Poppe No. 1,851,061, dated February 2, 1931. Alternatively, the longitudinal slits have been formed in the web of paper before it is formed into a tube, the transverse cuts being made after formation of the tube, such being shown in Poppe Patent No. 1,798,168.

For the carrying out of the indicated methods heretofore used, it has been necessary to provide a complicated system of knives and cutters to effectuate the longitudinal slitting, whether in the web or tube, and the transverse cutting. The necessary knives and cutters are costly to produce and maintain and difficult to adjust.

Now, in accordance with this invention, paper bags or envelopes having a long square cornered lip or closure flap may be efficiently produced by a simple and economic procedure and with apparatus which may be readily and inexpensively adopted to the usual machines for producing short flap bags or envelopes.

In the practical adaptation of this invention a web of paper is formed into a tube by the use of any usual forming mechanism and the tube fed over the end of the former in proximity to a fixed cut off blade, in cooperation with both of which a striker having transverse and longitudinal members periodically acts to sever bag lengths from the tube.

More specifically the edge of the fixed cut off blade is positioned above and behind the end of the former. The striker is provided with a transverse member which cooperates with the end of the former to transversely sever one wall of the tube and with the cut off blade to sever the other wall of the tube. The striker is also provided with longitudinal members which co-

operate with the edges of the former adjacent to its end to sever the edges of the tube longitudinally between the ends of the lines of transverse severance.

In practical operation the striker is driven at relatively high speed so that the transverse severance of one wall of the tube and the longitudinal slitting of the edges is effected substantially simultaneously and is followed immediately by transverse severance of the other wall with the result that the bag lengths are severed from the tube and the long lip or closure flap is formed in a single operation and substantially simultaneously in a simple, effective and economic manner without the addition of any new moving parts to the usual bag machine.

Having now indicated in a general way the nature and purpose of this invention, I will proceed to a detailed description of a preferred embodiment thereof with reference to the accompanying drawing in which:

Figure 1 is a plan view, partly in section, of an apparatus embodying this invention and adapted for the carrying out of the method of this invention.

Figure 2 is a perspective view of a bag or envelope produced in accordance with this invention.

Figure 3 is a plan view of the striker included in the apparatus of Figure 1.

Figure 4 is a sectional view showing a detail of construction of the striker in cooperation with the end of the former and with the cut off blade.

Figures 5 and 6 are sectional views showing details of the striker.

Referring to Figure 2 in which a bag or envelope having a long lip or closure flap is shown, it will be noted that the body of the bag A is closed at its bottom by means of a flap b and that closure of the top or open end is provided by a flap b'. The flaps b and b', it will be noted, are similar and are square cornered and of desired length. The flaps b' and b are produced in the severance of lengths from a paper tube, the walls of the tube being severed on spaced transverse lines and the opposite edges of the tube being severed on longitudinal lines joining the ends of the transverse lines of severance.

Referring now to Figures 1 and 3-6, c indicates a former such as is commonly used in envelope bag machines for forming a tube d from a web of paper e. The former may be of

110

any usual construction, as, for example, such as is illustrated and described in the Poppe patent above referred to, and is provided at its rear with a serrated edge *f*.

5 The web of paper is drawn about the former and the tube formed and advanced by means of rolls, *g*, *g*, mounted on a suitably driven shaft *h*, supported from a table *i*, and cooperating with the table to advance the tube beyond 10 the end *f* of the former.

Positioned above the former and to the rear of the edge *f* thereof is a cut off blade *j* supported from a bracket *k*, the edge of which is serrated and spaced from edge *f* of the former 15 a distance equal to the desired length of the flaps *b*, *b'* of the bag.

A striker *l* is mounted on a disc *m* and extends at an angle to the periphery of the disc so that on revolution of the disc the striker 20 will travel in a conical path as shown in Figure 1. The disc *m* is mounted on a shaft *n*, which is driven by any suitable mechanism (not shown) so that the striker is caused to periodically cooperate with the edge of the former and the edge of the cut off blade, as indicated by dotted lines, Figure 2.

The striker *l* comprises a transverse severing member *o* and spaced longitudinally extending severing members *p*, *p*.

30 The members *p*, *p* are similar and comprise blades *q*, mounted on supports *r* secured to and extending from the member *o*. The supports *r* are slidably mounted in a groove in member *o* and secured by means of machine screws extending through slots in member *o* as shown in 35 Figure 4. The slots enable adjustment of members *p*, *p* toward and away from each other for different size bags. The surfaces of the supports *r* are cut on an angle so that the blades will lie 40 thereon at an angle in their transverse extension as shown in Figure 6. The blades are provided with transversely extending slots *s* and are secured to supports *r* by means of clamps *t* secured to the supports by screws *u* which pass 45 through the slots *s* and permit the blades to be transversely adjusted, all as will be clear from inspection of Figures 5 and 6.

As will now be appreciated, in the operation 50 of the apparatus embodying my invention as above described, for the carrying out of the method embodying my invention, the web of paper *e* is formed into the tube *d* about the former *c*, being advanced as is the tube when formed by the rolls *g*. The tube *d* is advanced 55 beyond the end of the former and is severed into lengths by the action of the striker which is operated in timed relation to the advance of the tube so as to strike off or sever desired lengths.

60 In the operation of the striker, it will be noted that the member *o* cooperates with the end of the former and with the cut off blade to sever the sides of the tube *d* respectively, 65 while the members *p*, *p* cooperate with opposite edges *x*, *x* of the former adjacent its end to sever the edges of the tube longitudinally between the lines of severance of the sides. The action of the members *p*, *p* of the striker may 70 be readily perceived from inspection of Figures 4 and 6.

75 Thus, having the operation of the striker in cooperation with the end and edges of the former and with the cut off blade, desirably long square cornered flaps, as *b*', *b*' are formed

on each severance of a length from the tube *d*. As is obvious, the bag or envelope is completed by securing the flap *b* (Figure 2) in closing position.

What I claim and desire to protect by Letters 80 Patent is:

1. The method of producing a paper bag which includes continuously forming a tube from a web of paper and advancing the tube as formed, and while the tube is advancing striking lengths 85 from the tube on longitudinally spaced lines extending transversely of the walls of the tube and on lines extending longitudinally of the edges thereof between said transversely extending lines.

2. The method of producing a paper bag which includes continuously forming a tube from a web of paper and advancing the tube as formed, and while the tube is advancing severing 90 lengths from the tube in its advance by a substantially simultaneous severance of its walls transversely on longitudinally spaced lines and of its edges longitudinally between the ends of the lines of transverse severance.

3. The method of producing a paper bag 100 which includes forming a tube from a web of paper, advancing the tube relative to a pair of spaced severing edges extending transversely of the walls of the tube respectively and striking the tube adjacent to said edges while it is advancing to effect a severance of the walls of the tube transversely on longitudinally spaced lines and to effect a severance of the edges of the tube longitudinally between the ends of the lines 105 of severance of the walls thereof.

4. The method of producing a paper bag which includes forming a tube from a web of paper, advancing the tube relative to a pair of spaced severing edges extending transversely of the walls of the tube respectively, striking the 115 tube adjacent the side edges while the tube is advancing to effect a transverse severance of one wall of the tube on the line of one of said severing edges, then effecting a longitudinal severance of the edges of the tube between the 120 lines of said severing edges and finally transversely severing the other wall of the tube on the line of said other severing edge.

5. Apparatus for the formation of paper bags 125 including means for forming a tube from a web of paper, means for advancing the tube longitudinally as formed, a pair of severing edges positioned in the path of the tube as advanced and spaced from one another longitudinally with respect to the tube and a striker adapted to 130 periodically co-operate with one of said severing edges to sever one wall of the tube transversely and to sever the edges of the tube longitudinally and to co-operate with the other of said severing edges to sever the other wall of 135 said tube transversely.

6. Apparatus for the formation of paper bags 140 including means for forming a tube from a web of paper, means for advancing the tube longitudinally as formed, a pair of severing edges positioned in the path of the tube as advanced and spaced from one another longitudinally with respect to the tube and a striker having a transverse severing member and spaced longitudinal 145 severing members adapted to co-operate with said severing edges to effect transverse severance of the walls of the tube and longitudinal severance of the edges thereof between the lines of transverse severance.

7. Apparatus for the formation of paper bags including means for forming a tube from a web of paper, means for advancing the tube longitudinally as formed, a pair of severing edges positioned in the path of the tube as advanced and spaced from one another longitudinally with respect to the tube and a striker having a transverse severing member and spaced longitudinal severing members lying in planes at angles to the horizontal in their transverse extension adapted to co-operate with said severing edges to effect transverse severance of the walls of the tube and longitudinal severance of the edges thereof between the lines of transverse severance.

8. Apparatus for the formation of paper bags including means for forming a tube from a web of paper, means for advancing the tube longitudinally as formed, severing edges positioned in the path of the tube as advanced, said severing edges comprising a pair of edges spaced from one another longitudinally with respect to the tube and a pair spaced from one another transversely with respect to the tube and a striker comprising a transverse severing member and spaced longitudinal severing members, the transverse and longitudinal severing members of the striker being adapted to periodically cooperate with the longitudinally spaced and the transversely spaced severing edges, respectively, to effect severance of lengths from the tube on spaced transverse and longitudinal lines.

9. Apparatus for the formation of paper bags including means for forming a tube from a web of paper, means for advancing the tube longitudinally as formed, a severing edge positioned in the path of the tube as advanced and comprising a portion extending transversely of the tube and portions extending longitudinally thereof, a second severing edge positioned in the path of the tube as advanced and extending transversely of the tube, said first mentioned severing edge being positioned within the tube

and having its transverse portion spaced longitudinally ahead, in the direction of advance of the tube, of the second severing edge, said second severing edge being without the tube and a striker comprising a transverse member and a pair of spaced longitudinal members, said striker being adapted to periodically cooperate with said severing edges to effect severance of the walls of the tube on spaced transverse and longitudinal lines.

10. Apparatus for the formation of paper bags including means for forming a tube from a web of paper, means for advancing the tube longitudinally as formed, a pair of severing edges positioned in the path of the tube as advanced and spaced from one another longitudinally with respect to the tube and a striker comprising a transversely extending member, a pair of blades and means for adjustably securing said blades to said transverse member in spaced relation with respect to each other and angularly with respect to the said transverse member, said striker being adapted to periodically cooperate with said severing edges to effect severance of the walls of the tube along spaced transverse and longitudinal lines.

11. Apparatus for the formation of paper bags including means for forming a tube from a web of paper, means for advancing the tube longitudinally as formed, a pair of severing edges positioned in the path of the tube as advanced and spaced from one another longitudinally with respect to the tube and a striker comprising a transversely extending member, a pair of blades and means for adjustably securing said blades to said transverse member, said blades extending longitudinally with respect to said transverse member and lying in a plane at an angle to the horizontal, said striker being adapted to periodically cooperate with said severing edges to effect severance of the walls of the tube along spaced transverse and longitudinal lines.
